his ATTORNEY.

UNITED STATES PATENT OFFICE

EMIL R. WOHLER, OF CHICAGO, ILLINOIS.

BINDER.

1,336,495.

Specification of Letters Patent. Patented Apr. 13, 1920.

Application filed May 12, 1919. Serial No. 296,531.

To all whom it may concern:

Be it known that I, EMIL R. WOHLER, a citizen of the United States, and a resident of Chicago, Cook county, and State of Illinois, have invented certain new and useful Improvements in Binders, of which the following is declared to be a full, clear, and exact description.

This invention relates to binders and its 10 principal object is to provide improved and efficient means for binding together sheets of paper, such as bills, letters, or other memoranda. Another object is to provide a binder in which the sheets of paper may 15 be temporarily or permanently bound together at one corner, whereby practically all of any sheet may be exposed by turning back sheets thereabove along one corner of the binder. Another object is to provide a 20 binder for the corner of sheets, with means for positively holding the edges thereof in an even condition and with other means for securing them together. Another object is to provide a binder which may be used for 25 filing the sheets in vertical position and which permits the sheets to be laid on a desk or table, whereby they may be paged over and turned back at one corner to expose the desired sheet. With these and 30 other objects in view, this invention consists in the several novel features hereinafter fully described and claimed.

The invention is clearly illustrated in the accompanying drawing, in which:

35 Fig. 1 is a perspective view of a binder, embodying a simple form of the present invention, and showing fragments of sheets bound therein, the view illustrating the bound sheets held in a vertical position;

40 Fig. 2 is a perspective view of the binder, showing the bound sheets laid upon their sides;

Fig. 3 is a section of the binder taken on the line 3—3 of Fig. 1 and showing two 45 sheets held therein;

Fig. 4 is a section of the binder taken on the line 4—4 of Fig. 2;

Fig. 5 is a perspective view of the main corner member of the binder, and

50 Fig. 6 is a perspective view of the end member of the binder.

Referring to said drawing, the reference character 7 designates the corner member of the binder which, in its preferred form, is 55 made of sheet metal struck up with suitable dies, and comprises two sides, 8, 9, which

are disposed at right angles to each other, and an end 10 also disposed at right angles to the sides 8, 9, as is clearly illustrated in Fig. 5. The end 10 is substantially triangular in shape and its edge 11 extends at an angle of approximately 45 degrees with the corners 12, 13. Opposite the end 10 of the corner member 7, is an end member 13, which is also substantially triangular in shape and has two flanges, 14, 14, disposed at right angles to each other, and adapted to embrace the sides 8, 9, of the main member 7, as is clearly illustrated in Figs. 1 and 2. The edge 15 of the end 60 member 13 is disposed at an angle of approximately 45 degrees to the flanges 14, 14, and is the edge across which the leaves are turned back to expose any of the bound 65 leaves.

Extending through the end 10 of the member 7 is a screw or other threaded pin 16, which has a head 17 preferably held in a counter-sunk portion of the end 10. Upon the outer end of the screw-threaded 70 pin 16 is a nut or other internally threaded clamping member 18, which is arranged to bear against the outer face of the end member 13 to thereby secure it upon the corner member 7 and to bind the leaves or sheets 75 together.

It is preferred to use a piece of cardboard or other stiff material 19, at the end 10, which cardboard forms the bottom of the binder when the bound sheets are laid 80 upon their sides. I prefer to fasten said sheet of stiff material in place at the end 10, and have illustrated a nut 20 threaded upon the threaded stem 16 and bearing 85 against said strip of stiff material, as is clearly illustrated in Fig. 3.

The sheets or leaves 21 are provided with 90 perforations 22 for the reception of the threaded pin 16, and said perforations are made in the sheets near their lower left hand 100 corners and at such points as to bring the edges 23, 24, of the sheets in contact with the inner faces of the angularly disposed sides 8, 9, of the corner member 7, whereby, when said sheets are secured upon the 105 threaded pin 16, the edges thereof will be positively held in an even condition, thereby giving a neat and finished appearance to the bound sheets.

Obviously, any number of leaves or sheets 110 less than the full capacity of the binder may be secured together by the binder, and

other sheets may be added thereto until the full capacity of the binder is reached. To secure any number of sheets less than the number filling the capacity of the binder, or 5 to add any others thereto, the nut 18 and end member 13 are first removed from the screw-threaded pin 16, the sheets slipped upon the pin 16, and the end member 13 replaced upon the pin and moved down 10 along the inner faces of the sides 8, 9, as shown in dotted lines in Fig. 3, and brought into contact with the sheets and the nut 18 replaced on the screw-threaded stem and turned down against the end member 13. In this way a few sheets, or as 15 many as are placed upon the stem, may be firmly held in place. When the full capacity of the binder is reached, the cardboard, or other stiff material 19, and nut 20, may be removed if desired, and the sheet 20 of stiff material 19 may be replaced by a thinner outer sheet or cover and a similar cover sheet 25 placed on the opposite side of the stack of leaves, and the whole replaced 25 upon the stem 16 and fastened together by the end member 13 and nut 18.

Conveniently, an index card 26 may be placed upon the outer face of the side 8, of the corner member 7, and held in place 30 thereon by tongues 27 struck up from the body of the side 8 and bent down against the outer face of the index card, as is clearly shown in Fig. 1.

It is preferable to construct the corner 35 member and end member of light gage sheet metal for the sake of obtaining lightness, and it is also desirable that the end walls of the corner member and end member should be reinforced or made of suitable 40 thickness to withstand the strain placed upon them by the bolt and nut which tie the parts together. In Figs. 5 and 6 I have shown the corner member and end member as formed of light gage sheet metal, the 45 end walls being formed of double thickness of metal. In forming the end 10, of the corner member one ply 10^a is folded up from the side 9 and the other ply 10^b is folded forward from the side 8. The edge portion 10^c of the ply 10^b is folded over the edge of the ply 10^a and crimped down upon it. The end wall of the end member 13 is shown as constructed in the same manner.

The bound sheets may be conveniently 55 stored in upright position in suitable pigeon-holes or on shelves or racks, as seen in Fig. 1, the index card being exposed to view, and furnishing information for the selection of the proper group of bound sheets. When it 60 is desired to examine any bound sheet, the proper group is selected and laid upon its side, as shown in Fig. 2, in which position the sheets may be turned back along the edge 15 of the end member 13 to expose the 65 desired sheet. If it is desired to insert a

sheet at any place among the other sheets, the nut 18 and end member 13 are removed, the sheets separated from each other at the proper place, the sheet inserted and the sheets replaced on the stem and secured in 70 place by the end member and nut.

I claim as new and desire to secure by Letters Patent:

1. A binder comprising a corner member 75 consisting of two sides and an end disposed at right angles to each other to leave one open end, the two sides forming guides for one corner of the bound sheets; an end member for closing the open end of the corner member, and adjustable connecting 80 means between the end of the corner member and the end member, at least one end member having an oblique edge over which the sheets may be turned back.

2. A binder comprising a corner member 85 having two sides and an end disposed at right angles to each other, the two sides forming guides for one corner of the bound sheets; an end member opposite the end of the corner member; a screw-threaded stem 90 secured to the end of the corner member and extending through an aperture in the end member and a nut threaded upon said threaded stem and adapted to bear against the outer face of the end member, at least 95 one end member having an oblique edge over which the sheets may be turned back.

3. A binder comprising a corner member having two sides and an end disposed at 100 right angles to each other, the two sides forming guides for one corner of bound sheets; an end member disposed opposite to the end of the corner member and having flanges disposed at right angles to each other, arranged to overlap the sides of the 105 corner member; a screw-threaded stem extending through said end of the corner member and through the end member, and having a nut threaded thereon for securing the parts together.

4. A binder comprising a corner member 110 consisting of two sides and an end disposed at right angles to each other to leave one open end, the two sides forming guides for one corner of bound sheets; a screw-threaded 115 stem secured in the end of the corner member; an end member for closing the open end of said corner member and having an aperture for the reception of said threaded stem and capable of being moved along the 120 same, and a nut, threaded upon said stem for clamping said end member against the sheets to be bound, at least one end member having an oblique edge over which the sheets may be turned back.

5. A binder comprising a corner member 125 having two sides and an end disposed at right angles to each other, one of said sides being formed with outwardly punched tongues adapted to secure an index card to 130

the binder; an end member and a bolt and nut connecting said end of the corner member with the end member.

6. A binder comprising a corner member, having two sides and an end disposed at right angles to each other, the two sides forming guides for a corner of the bound sheets; an end member disposed at the side opposite the end of the corner member; a

bolt extending through said end of the corner member and end member; a nut on said bolt for securing the end member thereto; a cover of stiff material having an aperture for the reception of said bolt and a second nut threaded on said threaded member and bearing against said cover. 10 15

EMIL R. WOHLER.
